UNITED STATES PATENT OFFICE.

EPPA H. RYON, OF WALTHAM, MASSACHUSETTS, ASSIGNOR TO CROMPTON & KNOWLES LOOM WORKS, OF WORCESTER, MASSACHUSETTS, A CORPORATION OF MASSACHUSETTS.

TUBE-FRAME BRACKET.

Application filed March 22, 1923. Serial No. 626,826.

To all whom it may concern:

Be it known that I, EPPA H. RYON, a citizen of the United States, residing at Waltham, in the county of Middlesex and State 5 of Massachusetts, have invented a new and useful Tube-Frame Bracket, of which the following is a specification.

This invention relates to an end bracket or support for a tube frame of the type 10 used in Axminster carpet looms for inserting the pattern yarn tufts between the warp threads.

The present commercial tendency is to greatly increase the width of such looms, 15 with a corresponding increase in the length and width of yarn tube frames.

It is the general object of my present invention to perfect the construction of such tube frames by providing improved end 20 brackets or supports for detachably connecting the tube frames to the transporting pattern chains.

My improved brackets or supports are secured to the tube frames by a construction 25 which is extremely rigid and reliable and which cannot become detached or displaced under any reasonable conditions of use.

In the preferred form, this construction involves the use of an end block fitted with- 30 in the end of a tube frame and interlocked with portions of the frame and of the bracket so that all of the parts are firmly and rigidly secured together.

My invention further relates to arrangements and combinations of parts which will be hereinafter described and more particularly pointed out in the appended claims.

A preferred form of the invention is shown in the drawings in which—

40 Fig. 1 is a front elevation of a tube frame embodying my improvements;

Fig. 2 is an end elevation thereof;

Figs. 3 and 4 are detail sectional views, taken along the lines 3—3 and 4—4 in Fig. 45 2, and

Fig. 5 is a perspective view of the separated parts before assembly.

Referring to the drawings, I have shown a plurality of yarn tubes 10 mounted on a 50 rectangular tube frame 11; the tubes being secured thereto by soldering or in any other usual manner. Slits 12 in the bottom and top surfaces of the tube frame 11 extend in-

ward from the ends of the tube frame and provide tongues or projections 13 and 14 which preferably extend slightly beyond the side walls of the tube frame. 55

End blocks 15 are formed of rigid material such as die castings, the construction of the block being clearly shown in Fig. 5. 60 Grooves or recesses 16 are formed on the upper and lower ends of the block and the portion 17 of the block is of such dimensions as to fit closely within the tube frame 11. The outer portion 18 of the block is provided with a vertically extending groove or recess 19 adapted to receive a bracket or support 20 by which each end of the tube frame is attached to the pattern chain. 65

Springs 21 having hooks 22 at their upper 70 ends are secured to the brackets 20 by screws 23 and constitute means for detachably securing the brackets to the chains. A plate 24 is welded or otherwise secured to the inner side of the bracket 20, the upper end 75 thereof forming a spool bearing and the lower end being offset at 25 for a purpose to be explained.

Having described the details of construction of my improved tube frame bracket, 80 the method of assembling the parts is clearly indicated in Fig. 4. The blocks 15 are inserted in the ends of the tube frame 11 until shoulders 26 on the sides of the blocks engage the side walls of the tube frame. 85 The tongues or projections 13 and 14 are then bent inward by means of a press or hammer blow to the position indicated in Fig. 4, thus firmly securing the block in the end of the tube frame. The offset side 90 portion 25 of the bracket 20 is then inserted in the upper groove or recess 16 of the block 15 and the bracket is seated in the recess 19. The offset lower end 27 of the bracket 20 is then forced upward into the lower recess 95 16, completing the assembly of the parts.

From this description it will be apparent that my improved tube frame brackets are secured to the tube frame without the use of screws, studs or rivets and that the entire process of assembling the parts involves merely the bending of the tongues or projections 13, 14 and 27. 100

While I have described the assembling of the parts as taking place in two consecutive 105 steps, it will be evident that the bracket 20

may be placed in position on the block 15 before the latter is inserted in the tube frame and that the projections 13, 14 and 27, may be bent inward to lock the parts 5 together at a single operation if so desired.

Having thus described my invention and the advantages thereof, I do not wish to be limited to the details herein disclosed otherwise than as set forth in the claims, but 10 what I claim is:—

1. Means to support a tube frame comprising a block fitting within the end of said tube frame, means to secure said block in position, a supporting bracket, and means 15 to secure said bracket to said block.

2. Means to support a tube frame comprising a block fitting within the end of said tube frame and having recesses to receive inwardly offset portions of said tube frame 20 which thereby retain said block in position,

and a supporting bracket firmly secured to said block.

3. Means to support a tube frame comprising a block fitting within the end of said tube frame and having recesses to receive inwardly offset portions of said tube frame which thereby retain said block in position, and a supporting bracket having portions also seated in said recesses which 25 retain said bracket rigidly attached to said block and tube frame.

4. In a loom, a rectangular hollow metal tube frame, an end block and a tube frame bracket, said frame and said bracket having portions interlocked with said block to 30 secure said parts in fixed assembled relation.

In testimony whereof I have hereunto affixed my signature.

EPPA H. RYON.
